DETACHABLE SASH BALANCE

Glenn B. Haas, Oak Harbor, Ohio, assignor to Formetal, Inc., Oak Harbor, Ohio, a corporation of Ohio

Application September 29, 1954, Serial No. 459,107

5 Claims. (Cl. 16—202)

This invention relates to builder's hardware and, in particular, to window sash balances.

One object of this invention is to provide a detachable sash balance for removable sash windows having the capability of temporarily detaching and anchoring the coupling hook of the sash balance cable to the sash guide while the sash is removed, and of reattaching this hook when the sash is reinstalled after cleaning, repairs or other work thereon.

Another object is to provide a detachable sash balance for removable sash windows of the foregoing character, wherein the sash balance cable hook is automatically held in its retracted position when it is pushed backward to that position.

Another object is to provide a detachable sash balance for removable sash windows, of the foregoing character, wherein cam means is provided in connection with the window sash for automatically pushing the sash balance cable hook holder into its retracted position when the sash is raised after detachment of the cable hook, so that the hook and sash are prevented from interfering with one another during insertion or removal.

Other objects and advantages of the invention will become apparent during the course of the following description of the accompanying drawings: wherein:

Figure 1 is a vertical section through a double-hung sliding sash installation equipped with removable sash windows and with a detachable sash balance, according to one form of the invention;

Figure 2 is a horizontal section taken along the line 2—2 in Figure 1;

Figure 3 is an edge view of the upper portion of a window sash with the detachable sash balance cable hook secured to the keeper attached to the sash;

Figure 4 is an enlarged fragmentary front elevation, partly in section, of the sash balance cable hook immediately prior to its detachment from the keeper, with the cable hook holder projected into hook-intercepting position;

Figure 5 is a view similar to Figure 4, with the cable hook intercepted by the holder but not yet pushed out of the path of the keeper;

Figure 6 is a view similar to Figures 4 and 5, but showing the position of the cable hook immediately after its detachment from the keeper and pushed partly out of the path of the sash by the keeper cam;

Figure 7 is a view similar to Figures 4, 5 and 6, but showing the cable hook pushed completely out of the path of the sash into its fully retracted position;

Figure 8 is a right-hand side elevation of the mechanism shown in Figure 7;

Figure 9 is a horizontal section taken along the line 9—9 in Figure 8, showing the manner of securing the cable hook holder pivot pin to the housing;

Figure 10 is a section taken along the line 10—10 in Figure 8, showing the engagement of the cable hook with the cable hook holder;

Figure 11 is a perspective view of the construction shown in Figure 9, with the housing removed; and Figure 12 is an enlarged perspective view of the cable hook.

5 The recent widespread and increasing use of removable double-hung sliding sash windows for ease of cleaning or other maintenance or repairs has raised the problem of what to do with the spring sash balance connected to such window sash when the sash is removed. The separate attachment and detachment of the spring sash balance cord, cable, chain or tape every time the sash is removed and its reconnection when the sash is replaced in the window frame, is time consuming and annoying since it involves the coupling and uncoupling of parts while the operator is in an inconvenient position and also presents a hazard to eyesight or other parts of the body if the cable hook slips out of the grasp and is jerked upward suddenly by its spring.

The present invention provides a sash balance for removable sash windows which has a holder for receiving the cable hook and holding it temporarily with the cable in tension under the influence of its balancing spring while the sash is removed, cleaned and then replaced. The cable hook holder is so arranged as to be automatically 20 retracted by a cam when the sash is pushed upward, and held in its retracted position by a toggle action. The holder, however, is quickly and easily swung back into an intercepting path relatively to the keeper mounted on the sash when the sash is replaced in the window frame.

25 Referring to the drawings in detail, Figure 1 shows a double-hung removable sliding window sash installation, generally designated 10, including upper and lower sliding sash 12 and 14 slidably and yieldably mounted between metallic sash guides 16 of ribbed channel-shaped cross-section and yielding metallic sash guides 18 also of ribbed channel-shaped cross-section set into elongated vertical recesses 20 and 22 respectively in the opposite side members 24 and 26 of a window frame, generally designated 28. The window frame 28 has the usual sloping window sill 30 and top member or head 32 interconnected by the opposite side members 24 and 26, the construction being shown in simplified form for clearness of illustration.

30 The yielding sash guides 18, of which there are two 45 located side by side to receive the upper and lower sashes 12 and 14, are provided with ribs 34 which engage the adjacent grooves 36 in the window sashes 12 and 14 (Figure 2). The sash guides 18 are pushed into engagement with the grooves 36 by coil springs 38 coiled around fasteners 40 inserted in the window frame wide members 26. Contact between the springs 38 and the sash guide 18 is made by hollow contact elements 42 of channel-shaped cross-section (Figure 2) entering and engaging the grooves within the ribs 34.

35 50 The stationary sash guides 16 are of similar construction to the movable sash guide 18, being of channel-shaped form with hollow guide ribs 44 projecting inwardly therefrom into the grooves 46 on the opposite sides of the window sash 12 or 14 from the grooves 36. The stationary sash guides 16 are secured in any suitable way, as by the fasteners 48 to the window frame side members 24, and contain sash balances, generally designated 49. For purposes of simplification, only the sash balance 49 for the lower sash 14 is shown in the drawings, it being understood that the upper sash 12 may be similarly provided if desired.

40 45 The stationary sash guide 16, being of approximately channel-shaped cross-section as above, serves as a housing for an elongated helical tension spring or balancing spring 50, the lower end of which is anchored to the spring bracket 52 which in turn is secured as at 54 to the interior of the lower end portion of the hollow guide rib

44. The upper end of the balancing spring 50 is connected to the inner end 56 of a sash balance cable 58 which passes around a pulley 60 mounted upon an axle 62, the opposite ends of which are supported in the guide rib 44 and reinforced by plates 64.

Secured to the outer end 66 of the cable 58 is a cable hook, generally designated 68 (Figure 12), the said outer end 66 being in the form of an approximately triangular loop, the sides of which engage notches 70 in the bridge portion 72 of the cable hook 68, which has a forward hook portion 74 and a rearward reversely-bent portion 76 extending over the loop 66 and into close proximity to the hook portion 74. The loop 66 is held in its closed position by a fastener 78 (Figure 8).

The hook portion 74 of the cable hook 68 normally is hooked into a vertically-elongated aperture 80 and beneath a bridge portion 82 formed thereby in a cable hook keeper, generally designated 84 (Figures 3 and 4). The cable hook keeper 84 at the lower end portion 86 is in substantially the same plane as the upper portion 88, while between them lies a wedge-shaped hump 90 with oppositely-inclined rise and fall portions 92 and 94 respectively meeting one another in a peak 96. The lower portion 86 of the keeper 84 is drilled as at 98 to receive fasteners 100 by which it is secured in a recess 102 formed in the upper corner of the sash 14, with a counter-recess 104 extending below the level of the upper end of the recess 102 in order to accommodate the hook portion 74 of the cable hook 68 without interference. By reason of this construction, the upper portion 88 of the keeper 84 is spaced away from the bottom of the counter-recess 104, whereas the lower portion 86 solidly abuts the bottom of the recess 102.

The cable hook 68 and cable 58 when not in use or while being withdrawn from engagement with the bridge portion 82 of the keeper 84, are held in a tensioned condition by a swinging holder, generally designated 106 (Figures 4 and 8 to 11 inclusive), pivotally mounted in an elongated opening 105 in the front wall 107 of the projecting rib portion 44 of the stationary sash guide and housing 16. The holder 106 consists of an elongated plate 108 of sheet metal (Figure 8) having an elongated central aperture 110 and pivot elements or trunnions 112 extending laterally from slightly above the midportion thereof. The slotted plate 108 is divided into upper and lower portions 114 and 116 respectively tilted relatively to one another at an obtuse angle, the apex of which is located substantially on the pivot axis 117 of the pivot elements 112, the lower portion 116 being of slightly greater length than the upper portion 114. The extreme lower end of the lower portion 116 is provided with laterally-spaced L-shaped lugs 118 projecting toward one another from the opposite edges thereof (Figure 8) and having notches 120 facing one another for receiving the opposite ends of the loop 66, the space 122 between the lugs 118 being less than the width of the cable hook 68 in order to firmly hold the opposite ends of the cable hook 68 while permitting the loop 66 and cable 58 to pass between them (Figure 8).

The pivot elements or trunnions 112 are seated in notches 124 (Figure 9) in the side walls of the rib portion 44, and held in position by a wire bridle, generally designated 126 (Figures 4, 9 and 11). The wire bridle 126 is of approximately U-shaped form with upper and lower courses 128 and 130 respectively looped around the pivot elements 112 as at 132 and extending behind a channel member 134, where they are secured to one another by twisting as at 136 (Figures 9 and 11). The bottom 137 of the channel member 134 has arcuately-bent upper and lower end extensions 138 and 140 respectively (Figure 4). The bottom 137 of the channel member 134 is also drilled with vertically-spaced holes 142 and 144 which receive the upper or base portion 146 of a leaf spring 148 (Figures 4 and 8). The upper end portion 150 of the base portion 146 is bent at right angles to

to the bottom 137 of the channel member 134 in order to secure it in position, whereas the lower end portion 152 extends arcuately outward through the slot 110 into engagement with the lower portion 116 of the slotted plate 108 of the holder 106 so as to urge the lower portion 116 of the slotted plate 108 of the holder 106 so as to urge the lower portion 116 inwardly toward the bottom 137 of the channel member 134. In order to prevent interference between the spring 50 and the parts secured to the channel member 134, a sheet metal guard 154 is disposed from top to bottom of the channel member 134 with its upper and lower ends 156 and 158 bent around and hooked over the curved upper ends 138 and 140 of the channel member bottom portion 137.

In the operation of the invention, let it be assumed that the upper and lower sashes 12 and 14 are in their closed positions (Figure 1) and that the cable hook 68 is connected to the keeper 84 with the cable 58 in a state of tension due to the stretching of the tension spring 50. To detach the cable hook 68, and hold it in a retracted position in order to remove and subsequently replace the lower sash 14, the operator raises the lower sash 14 while he presses the upper portion 114 of the holder 106 inward around its pivot elements 112 so as to project the lugs 118 into the path of the cable hook 68. The operator continues to raise the sash 14 while holding the lugs 118 in their extended position (Figure 4) until the connecting portion 72 of the cable hook 68 engages the lugs 118, with the loop 66 of the cable 58 passing through the space 122 beneath the lugs 116 and entering the notches 120 (Figure 8).

The operator continues to raise the sash 14 from the position of Figure 4 to the position of Figure 5, causing the bridge portion 82 of the cable hook keeper 84 to detach itself from the hook portion 74 of the cable hook 68 while the latter is held by the lugs 118. With the cable hook 68 occupying the slot 80 in the upper portion 88 of the keeper 84, the operator continues to raise the sash 14 from the position of Figure 5 to that of Figure 6, causing the rise 92 of the cam portion 90 to engage the cable hook portion 74 and push the latter backward, until the peak 96 pushes the cable hook portion 74 into the retracted position of Figure 7. While this is occurring, the lower portion of the cable hook 68 passes rearwardly toward the pivot axis 117 of the pivot elements 112 (Figure 7), neutralizing the pull of the cable 58 upon the lower end or lugs 118 of the holder 106 by causing the line of action of the force exerted by the cable 58 to pass substantially through or slightly behind the pivot axis 117. The slot 110 in the plate 108 enables the lower part of the cable 58 to assume this position of Figures 7 and 8. The leaf spring portion 152 of the spring 148 is then enabled to exert an overbalancing force to hold the cable hook 68 and cable hook holder 106 in their fully retracted positions of Figure 7, located completely within the interior of the hollow rib 44. The operator then lowers the sash 14, as in Figure 7, whereupon he pushes it to the right to compress the springs 38 (Figure 2) and at the same time withdraw the groove 46 from engagement with the rib 44. The left-hand edge of the sash 14 is then pulled forward to completely withdraw it from the window opening, whereupon the sash 14 is then pulled outward obliquely to the left to detach it from the rib 34 of the movable sash guide 18 and remove it completely from the window opening.

To replace the window sash 14 in the window opening and reattach it to the cable hook 68 of the sash balance 49, the operator reverses the above-described procedure, the cable hook 68 and holder 106 being in the retracted positions shown in Figure 7. The operator inserts the sash 14 obliquely into the window opening with the groove 36 engaging the guide rib 34 of the movable sash guide 18 (Figure 2) pushing inward to the right until the left-hand side of the sash 14 passes the guide rib 44 in the stationary sash guide 16 and enters the guide groove 46.

The operator then releases the sash 14 which is pushed to the left by the coil springs 38 to cause the groove 46 to seat itself around the guide rib 44 in a position below the cable hook holder 106.

The operator now raises the sash 14 from the position of Figure 7 until the opening 80 therein arrives opposite the cable hook 68, whereupon he presses inward with his finger upon the upper portion 114 of the plate 116 of the cable hook holder 106, interposing the hook portion 74 of the cable hook 68 in the path of the bridge portion 82 of the keeper 84 (Figure 5). As the cable 58 swings outward past the pivot axis 117 of the holder 106 from the position of Figure 7 to that of Figure 5, the tension of the balancing spring 50 holds the cable hook 68 in its projected position (Figure 5), overpowering the leaf spring 148. The operator then lowers the sash 14 and keeper 84 until the hook portion 74 of the cable hook 68 engages and hooks around the bridge portion 82 thereof (Figure 4), whereupon the operator continues to lower the sash 14, carrying downward with it the cable hook 68, detaching the cable hook 68 from engagement with the lugs 118 of the holder 106. The force of the leaf spring 148 then snaps the holder 106 backward into its retracted position (Figure 1) and the parts occupy their starting positions shown in Figure 1.

What I claim is:

1. A detachable sash balance construction for a sliding sash window removably mounted in a window frame and sash guide structure, said construction comprising a cable hook keeper adapted to be attached to the sash, a cable hook detachably engageable with said keeper, a flexible cable secured to said cable hook, a sash-balancing force-applying element mounted in said structure and connected to said cable, a cable hook holder pivotally mounted on said structure for swinging motion into and out of intercepting relationship with said cable hook, said cable hook holder including an elongated lever disposed in a generally up-and-down direction with its pivotal mounting disposed intermediate its ends, and means for normally resiliently urging said lever out of intercepting relationship with said hook.

2. A detachable sash balance construction for a sliding sash window removably mounted in a window frame and sash guide structure, said construction comprising a cable hook keeper adapted to be attached to the sash, a cable hook detachably engageable with said keeper, a flexible cable secured to said cable hook, a sash-balancing force-applying element mounted in said structure and connected to said cable, and a cable hook holder pivotally mounted on said structure for swinging motion into and out of intercepting relationship with said cable hook, said cable hook holder including an elongated lever disposed in a generally up-and-down direction with its pivotal mounting disposed intermediate its ends, said lever having an elongated opening therein adjacent and extending longitudinally in opposite directions from said pivot and

providing clearance for said cable during swinging of said lever to and fro.

3. A detachable sash balance construction for a sliding sash window removably mounted in a window frame and sash guide structure, said construction comprising a cable hook keeper adapted to be attached to the sash, a cable hook detachably engageable with said keeper, a flexible cable secured to said cable hook, a sash-balancing force-applying element mounted in said structure and connected to said cable, a cable hook holder pivotally mounted on said structure for swinging motion into and out of intercepting relationship with said cable hook, said cable hook holder including an elongated lever disposed in a generally up-and-down direction with its pivotal mounting disposed intermediate its ends, said lever having an elongated opening therein extending past said pivot and adapted to receive said cable, and means for normally resiliently urging said lever out of intercepting relationship with said hook.

20 4. A detachable sash balance construction for a sliding sash window removably mounted in a window frame and sash guide structure, said construction comprising a cable hook keeper adapted to be attached to the sash, a cable hook detachably engageable with said keeper, a flexible cable secured to said cable hook, a sash-balancing force-applying element mounted in said structure and connected to said cable, and a cable hook holder movably mounted on said structure for travel into and out of intercepting relationship with said cable hook, said keeper 25 having a cam portion thereon engageable with said hook and responsive to the sliding of the sash in the sash guide structure for urging said hook from a keeper-engaging position into a keeper-avoiding position.

5. A detachable sash balance construction for a sliding sash window removably mounted in a window frame and sash guide structure, said construction comprising a cable hook keeper adapted to be attached to the sash, a cable hook detachably engageable with said keeper, a flexible cable secured to said cable hook, a sash-balancing force-applying element mounted in said structure and connected to said cable, and a cable hook holder pivotally mounted on said structure for swinging motion into and out of intercepting relationship with said cable hook, said cable hook holder including an elongated lever disposed in an approximately vertical position with its pivotal mounting disposed intermediate its ends, said keeper having a cam portion thereon engageable with said hook and responsive to the sliding of the sash in the sash guide structure for urging said hook from a keeper-engaging position into a keeper-avoiding position.
